ATTORNEY

UNITED STATES PATENT OFFICE.

HENRY L. THOMPSON, OF PHILADELPHIA, PENNSYLVANIA.

DESIGN FOR A CARPET.

58,840.

Specification for Design.

Patented Aug. 30, 1921.

Application filed November 6, 1920. Serial No. 422,400. Term of patent 3½ years.

To all whom it may concern:

Be it known that I, HENRY L. THOMPSON, a citizen of the United States, residing at Philadelphia, in the county of Philadelphia and State of Pennsylvania, have invented a new, original, and ornamental Design for a Carpet, of which the following is a specification, reference being had to the accompanying drawings, forming a part thereof.

The showing is a plan view of a portion of the carpet embodying the design.

I claim:

The ornamental design for a carpet as shown.

HENRY L. THOMPSON.

Witnesses:

HARRY ROWEN,

J. WALTER BRAND.
